BRACKET FASTENING MEANS FOR TEXTILE DRAWING MECHANISMS

Erwin Dausch, Esslingen (Neckar), Germany, assignor to S. K. F. Kugellagerfabriken, G. m. b. H., Schweinfurt, Germany

Application November 16, 1954, Serial No. 469,225

Claims priority, application Germany April 10, 1954

8 Claims. (Cl. 19—134)

The present invention relates to textile drawing mechanisms used in spinning machines.

With such drawing mechanisms it is conventional to provide on a stationary frame a bracket which turnably carries a top rolls carrying arm for movement to and from an operating machine. This bracket is conventionally fixed to a bar carried by the frame. The fixing of the bracket to the bar is usually brought about by providing the bracket with a pair of springy free end portions passing about the bar and drawn together by a screw or the like into clamping engagement with the bar. With this conventional feature it is exceedingly difficult if not impossible to provide a good connection between the bracket and bar because the springy free end portions of the bracket very seldom if ever have in engagement with the bar surfaces which correspond exactly to the shape of the bar so that clamping engagement between the bracket and the bar over the entire clamping surface of the free end portions of the bracket can be obtained under the best possible circumstances only if these free end portions are drawn toward each other with a tremendous force, and the exertion of such a force is of course undesirable.

One of the objects of the present invention is to overcome the above drawbacks by providing a means on the bracket capable of clamping the bracket to the bar with an extremely large force after application of a small fraction of this large force to this means.

Another object of the present invention is to provide a bracket of the above type with a clamping means which fixes the bracket to the bar in a manner far superior to anything which has hitherto been possible.

A further object of the present invention is to provide a bracket and a clamping means of the above type both of which are of an exceedingly simple and compact construction.

With the above objects in view the present invention mainly consists of a textile drawing mechanism which includes a support means carrying a bar. A bracket is formed with an opening through which the bar extends, and this bracket is adapted to carry a top rolls carrying arm of the drawing mechanism. This bracket has a portion spaced from the bar and provided with a surface directed toward the bar. A wedge member is located in the space between the bracket portion and bar and engages the latter and the surface of the bracket portion. A means engages this wedge member for wedging the same into this space against the bar and this surface of the bracket portion so as to fix the bracket to the bar.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a fragmentary, diagrammatic side elevational view of a textile drawing mechanism including the structure of the invention;

2

Fig. 2 is a fragmentary sectional view showing the details of the invention on an enlarged scale as compared to Fig. 1, Fig. 2 being taken along line 2—2 of Fig. 3 in the direction of the arrows; and

5 Fig. 3 is a sectional view taken along line 3—3 of Fig. 2 in the direction of the arrows.

Referring now to Fig. 1, it will be seen that the textile drawing mechanism illustrated therein includes a frame A to which a bracket B is fixed. A top rolls carrier C is turnably carried by the bracket B for movement from the operating position shown in Fig. 1 in a clockwise direction upwardly to an inoperative position. Blocks 20 which turnably carry the bottom rolls 41, respectively, are shiftable along the frame A in a known way to adjust the position of the bottom rolls. The top rolls carrier C has arms 23 connected thereto, and these arms 23 turnably carry the top rolls 22, respectively, these top rolls also being adjustable in a known way so as to properly engage the bottom rolls, respectively. Also, Fig. 1 diagrammatically shows clearer rolls 39 respectively in engagement with the top rolls 22. A releasable lock member 14 and a rivet 35 are also visible in Fig. 1 and are referred to in greater detail below.

25 The details of the structure of the invention are shown in Figs. 2 and 3 which show the bracket B and the parts of the drawing mechanism associated therewith. This bracket B is made out of a springy sheet metal bent in a press or the like to the shape shown in Figs. 2 and 3.

30 The bracket B includes a pair of side walls 24 and 25 which are spaced from each other and interconnected by a rear wall 26 of the bracket. The bracket is formed between the side walls 24 and 25 with a lower cutout 27 and an upper cutout 28, as shown in Figs. 2 and 3, so that the side walls 24 and 25 are interconnected only by the rear wall 26, and in this way the side walls 24 and 25 are resiliently movable toward and away from each other. The rear wall 26 is formed with an opening 29 for a purpose described below.

35 40 Each of the side walls 24 and 25 is provided with an inwardly pressed portion having a surface directed toward the bar 10. This bar 10 is fixed to the frame A. Thus, as is particularly evident from Fig. 3, the side wall 24 is provided with an inwardly struck portion 32 bent at 30 inwardly from the side wall 24, and the side wall 25 is provided with an inwardly struck portion 33 bent at 31 inwardly from the side wall 25. These inwardly struck portions 32 and 33 are cut from material of the side walls 24 and 25, respectively, and are respectively provided with surfaces directed toward and spaced from the bar 10, these surfaces being located at the free edges of the inwardly struck portions 32 and 33, respectively. As is apparent from Fig. 3, the portions 32 and 33 make the same acute angle with the remainder of the side walls 24 and 25, respectively, and the free edges of the portions 32 and 33 are parallel to each other and located opposite each other. The side walls 24 and 25 are respectively formed with aligned openings of substantially

50 55 60 65 70 the same diameter as bar 10 and through which the bar 10 extends.

A pair of wedge members 16 and 17 are located within the bracket B between the side walls 24 and 25 thereof, and, as is evident from Fig. 3 where the front end face of wedge member 17 is visible, these wedge members have a width substantially equal to the distance between side walls 24 and 25. The wedge member 16 is provided with a bottom inclined surface portion 161 engaging bar 10 and the wedge member 17 is provided with a bottom inclined surface portion 171 engaging the bar 10, and as is evident from Figs. 2 and 3, these

wedge members are located in the space between bar 10 and portions 32 and 33 and engage the bar 10 and the surfaces of portions 32 and 33 which are directed toward the bar 10. The wedge member 17 is formed in its top face directed toward the inwardly struck portions 32 and 33 with a channel having opposed side faces of the same inclination as and respectively engaging the outer side faces of the inwardly struck portions 32 and 33, so that the wedge member 17 is provided along its length with an upper rib 172 located between inwardly struck portion 32 and the remainder of side wall 24 and with an upper rib 173 located between inwardly struck portion 33 and side wall 25. In the same way, the wedge member 16 is formed in its top face with a channel having opposed side faces of the same inclination as and engaging the outer side surfaces of the inwardly struck portions 32 and 33, so that wedge member 16 has along one of its upper side edges a rib 162 located between inwardly struck portion 32 and the remainder of side wall 24, as shown in Fig. 2, and along its upper side edge opposite rib 162 with a second rib not visible in the drawings located between the inwardly struck portion 33 and side wall 25 in alignment with the rib 173 of the wedge member 17. As is evident from Fig. 2, the inwardly struck portions 32 and 33 are substantially longer than the total length of the wedge members 16 and 17 which engage these inwardly struck portions.

The wedge member 17 is formed with a bore passing therethrough and the wedge member 16 is formed with a bore aligned with the bore of wedge member 17 and being coaxial therewith. A screw 18 extends freely through the bore of wedge member 17 into threaded engagement with the bore of wedge member 16, and the head of screw 18 bears against the right end face of wedge member 17, as shown in Fig. 2. The head of screw 18 is in alignment with opening 29 and is formed at its right end face, as viewed in Fig. 2, with a non-circular recess adapted to receive a key wrench passing through opening 29 into engagement with the screw member 18 for turning the latter. Thus, by turning the screw 18 the wedge members 16 and 17 are drawn toward each other into the space between bar 10 and portions 32 and 33 into wedging engagement with the latter and bar 10 so as to fix the bracket to the bar 10 in this manner. When the bracket is fixed in this manner to the bar 10 the force of the wedge members against the inwardly struck portions 32 and 33 is transferred through the latter to the bracket so as to press the latter against the bar 10. The inclined surfaces 161 and 171 of wedge members 16 and 17, respectively, enable these wedge members to be pressed against the bar 10 with a force several times as great as the force applied by the operator to the screw 18, and the designer is free to fix the relationship between these forces by choosing the particular inclination of the surfaces 161 and 171.

The top rolls carrier C is in the form of a channel member 13 made of sheet metal and open along its bottom. The side walls of the channel member 13 are provided at their rear end portions with outwardly pressed parts 131, respectively, and the upper portions of the side walls 24 and 25 are accommodated between these portions 131 of channel member 13. The pivot pin 12 extends through aligned openings in side walls 24 and 25, respectively, and through aligned openings in the portions 131 of member 13, respectively, so that in this way the top rolls carrier C is supported for turning movement on the bracket B. Pins 34 respectively extend through transverse bores formed in the pivot pin 12 (Fig. 3), and these pins respectively engage the outer faces of portions 131 of member 13 so as to prevent axial displacement of pivot pin 12.

As is well known, springs mounted on top rolls carrier C urge the top rolls 22 downwardly into engagement with the bottom rolls 41, respectively, and these springs tend to turn the top rolls carrier C upwardly from the

operating position shown in Fig. 1. In order to prevent such turning of the top rolls carrier C, a lock 14 is provided. This lock 14 extends about the channel member 13 and is provided with a bottom cross piece 141 engaging the forward projections 111 of side walls 24 and 25, respectively, so that in this way the lock 14 prevents upward turning of the top rolls carrier. The top wall of channel member 13 is provided with an upwardly extending, part cylindrical projection extending into a mating recess formed in the underside of the top portion of lock 14 so that in this way the lock 14 is turnable on the channel member 13. Thus in order to release the top rolls carrying arm C for turning movement to an inoperative position, it is only necessary to turn the lock 14 in a clockwise direction, as viewed in Fig. 2, so as to move cross piece 141 out of engagement with projections 111. The lock 14 is provided with a downwardly extending projection 142 passing with substantial clearance through an opening in the top wall of channel member 13, and this projection 142 is itself formed with an opening through which a wavy leaf spring 15 extends, as shown in Fig. 2, this leaf spring engaging the underside of the top wall of channel member 13 and projection 142 to resiliently urge the lock 14 to its locking position shown in Fig. 2.

A rivet 35 fixes to the underside of the top wall of channel member 13, adjacent its rear end, a leaf spring 36 having a curved free end portion 37 which enters into a recess 38 formed in the outer rear face of rear wall 26 of bracket B when arm C is turned upwardly to its inoperative position, so that in this way the leaf spring 36 cooperates with bracket B to releasably retain the arm C in its upper inoperative position.

It will be understood that each of the elements described above, or two or more together, may also find a useful application in other types of textile drawing mechanisms differing from the types described above.

While the invention has been illustrated and described as embodied in brackets for textile drawing mechanisms, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In a textile drawing mechanism, in combination, support means; a bar carried by said support means; a bracket adapted to carry a top rolls carrying arm of the drawing mechanism, said bracket having a pair of spaced side walls respectively formed with aligned openings through which said bar extends and each of said side walls having an inwardly extending portion spaced from said bar and having a surface directed toward the same, said portions of said side walls being located opposite each other; a wedge member located in the space between said bracket portions and bar and engaging the latter and said surfaces of said bracket portions; and means engaging said wedge member for moving the same into wedging engagement with said bar and bracket portions for fixing said bracket to said bar.

2. In a textile drawing mechanism, in combination, support means; a bar carried by said support means; a bracket adapted to carry a top rolls carrying arm of the drawing mechanism, said bracket having a pair of spaced side walls respectively formed with aligned openings through which said bar extends and each of said side walls having an inwardly extending portion cut from the re-

mainder of said bracket and having a free edge directed toward and spaced from said bar, said inwardly extending portions of said side walls being located opposite each other; a wedge member located in the space between said bracket portions and bar and engaging the latter and said edges of said inwardly extending bracket portions; and means engaging said wedge member for moving the same into wedging engagement with said bar and bracket portions for fixing said bracket to said bar.

3. In a textile drawing mechanism, in combination, support means; a bar carried by said support means; a bracket adapted to carry a top rolls carrying arm of the drawing mechanism, said bracket having a pair of spaced side walls respectively formed with aligned openings through which said bar extends and each of said side walls having an inwardly extending portion cut from the remainder of said bracket and having a free edge directed toward and spaced from said bar, said inwardly extending portions of said side walls being located opposite each other; a pair of wedge members spaced from each other, located in the space between said bracket portion and bar, and engaging the latter and said edges of said inwardly extending bracket portions; and means engaging said wedge members for drawing the same toward each other into wedging engagement with said bar and bracket portions for fixing said bracket to said bar.

4. In a textile drawing mechanism, in combination, support means; a bar carried by said support means; a sheet metal bracket adapted to carry a top rolls carrying arm of the support means, said bracket having a pair of spaced side walls respectively formed with aligned openings through which said bar extends and each of said side walls having an inwardly extending portion cut from said bracket side wall, making an acute angle therewith, and having a free edge directed toward and spaced from said bar, said inwardly extending portions of said side walls being located opposite each other; a wedge member located in the space between said bracket portions and bar and engaging the latter, said wedge member having a face directed toward said bracket portions and formed with a channel into which said bracket portions extend with outer side surfaces of said bracket portions respectively engaging side surfaces of said channel; and means engaging said wedge member for moving the same into wedging engagement with said bar and bracket portions for fixing said bracket to said bar.

5. In a textile drawing mechanism, in combination, support means; a bar carried by said support means; a bracket adapted to carry a top rolls carrying arm of the drawing mechanism, said bracket having a pair of spaced side walls respectively formed with aligned openings through which said bar extends and each of said side walls having an inwardly extending portion spaced from said bar and having a free edge directed toward the same, said portions of said side walls being located opposite each other; a pair of wedge members spaced from each other, located in the space between said bracket portion and bar, and engaging the latter and said edges of said inwardly extending bracket portions; and means engaging said wedge members for drawing the same toward each other into wedging engagement with said bar and bracket portions for fixing said bracket to said bar.

6. In a textile drawing mechanism, in combination, support means; a bar carried by said support means; a sheet metal bracket adapted to carry a top rolls carrying arm of the support means, said bracket having a pair of spaced side walls respectively formed with aligned openings through which said bar extends and each of said side walls having an inwardly extending portion cut from said bracket side wall, making an acute angle therewith, and having a free edge directed toward and spaced from said bar, said inwardly extending portions of said side walls being located opposite each other and respectively making the same angles with said side walls; a wedge member located in the space between said bracket portions and bar and engaging the latter, said wedge member having

a face directed toward said bracket portions and formed with a channel into which said bracket portions extend, said channel having side surfaces of the same inclination as said bracket portions, respectively, engaging the outer surfaces of said bracket portions, respectively; and means engaging said wedge member for moving the same into wedging engagement with said bar and bracket portions for fixing said bracket to said bar.

7. In a textile drawing mechanism, in combination, support means; a bar carried by said support means; a sheet metal bracket adapted to carry a top rolls carrying arm of the support means, said bracket having a pair of spaced side walls respectively formed with aligned openings through which said bar extends and each of said side walls having an inwardly extending portion cut from said bracket side wall, making an acute angle therewith, and having a free edge directed toward and spaced from said bar, said inwardly extending portions of said side walls being located opposite each other and respectively making the same angles with said side walls; a pair of wedge members located in the space between said bracket portions and bar and engaging the latter, said wedge members being spaced from each other and respectively having faces directed toward said bracket portions and formed with channels, respectively, into which said bracket portions extend, said channels each having side surfaces of the same inclination as said bracket portions, respectively, engaging the outer surfaces thereof, respectively; and means engaging said wedge members for drawing the same toward each other into wedging engagement with said bar and bracket portions for fixing said bracket to said bar.

8. In a textile drawing mechanism, in combination, support means; a bar carried by said support means; a bracket adapted to carry a top rolls carrying arm of the drawing mechanism, said bracket having a pair of spaced side walls respectively formed with aligned openings through which said bar extends and a rear wall interconnecting said side walls and also formed with an opening, each of said side walls having an inwardly extending portion spaced from said bar and having a surface directed towards the same, said inwardly extending portions of said side walls being located opposite each other; a pair of wedge members respectively located in the space between said side walls between said bar and said inwardly extending portions of said side walls and engaging said inwardly extending portions of said side walls and said bar, said wedge members being spaced from each other and respectively formed with coaxial bores passing therethrough, the bore of that wedge member which is most distant from said rear wall of said bracket having its bore threaded; and a screw member extending freely through the other of said bores into threaded engagement with said threaded bore for drawing said wedge members toward each other into wedging engagement with said bar and said inwardly extending portions of said bracket side walls so as to fix said bracket to said bar, said screw member having a head end accessible through said opening in said rear wall of said bracket and said wedge members and screw member being located in their entirety between said side walls of said bracket so that the entire structure for fixing said bracket to said bar does not extend outwardly beyond said bracket.
